DESIGN FOR A LAVATORY

George W. Kohlmeyer, Buffalo, N. Y., and James Fraser, Wilmington, Del., assignors to W. A. Case & Son Manufacturing Company, Buffalo, N. Y., a corporation of New York, and Speakman Company, Wilmington, Del., a corporation of Delaware, jointly

Application August 8, 1939, Serial No. 86,536

Term of patent 14 years

To all whom it may concern:

Be it known that we, George W. Kohlmeyer, a citizen of the United States, residing at Buffalo, in the county of Erie and State of New York, and James Fraser, a citizen of the United States, residing at Wilmington, in the county of New Castle and State of Delaware, have jointly invented a new, original, and ornamental Design for a Lavatory, of which the following is a specification, reference being had to the accompany drawing, forming part thereof.

In the accompanying drawing:

Fig. 1 is a perspective view of the lavatory showing our design.

Fig. 2 is a top plan view thereof.

Fig. 3 is a front elevation of the same.

Fig. 4 is a side elevation thereof.

Fig. 5 is a rear elevation of the same.

Fig. 6 is a vertical section taken on line 6—6,

Fig. 3.

We claim:

The ornamental design for a lavatory, as shown.

GEORGE W. KOHLMAYER.
JAMES FRASER.
